CLAIM

The ornamental design for a disc brake calliper, as shown and described.

DESCRIPTION

FIG. 1 is a perspective view of a disc brake caliper showing my new design;

FIG. 2 is an end view thereof;

FIG. 3 is another end view thereof, opposite that of FIG. 2;

FIG. 4 is a side view thereof;

FIG. 5 is a side view thereof, from a side opposite that of FIG. 4;

FIG. 6 is a top view thereof; and,

FIG. 7 is a bottom view thereof.

The broken lines and areas within them illustrate portions of the disc brake caliper that form no part of the claimed design.
